DAYLIGHT DEVELOPING APPARATUS

Filed April 11, 1931

INVENTOR
GEORGE A. MAGNUS.

BY *Robert S. Young*
ATTORNEY

UNITED STATES PATENT OFFICE

GEORGE A. REAGAN, OF DAYTON, OHIO

DAYLIGHT DEVELOPING APPARATUS

Application filed April 11, 1931. Serial No. 530,401.

(GRANTED UNDER THE ACT OF MARCH 3, 1929, AS AMENDED APRIL 20, 1930; 370 O. G. 757)

The invention described herein may be manufactured and used by or for the Government for governmental purposes, without the payment to me of any royalty thereon.

The present invention relates generally to photography and more particularly to improvements in photographic film developing and fixing apparatus which is especially adapted to be rapidly operated in the day-light.

A primary object of the present invention is to provide means for treating photographic plates or films after exposure to the light, said invention providing in part novel means whereby a photographic plate or film may be subjected to the action of fluids either for developing or fixing or washing the same and to accomplish this end without resorting to the use of a dark room.

A further object of the present invention is to provide a portable receptacle and closure therefor, which will guard a photographic plate or film contained therein against rays of actinic light while the said plate or film is being subjected to the action of the fluid or fluids.

A further object of the present invention is to provide in a container of the aforementioned character means cooperating with the photographic plate or film adapted for rendering the same light-tight by forming a light seal when the adapter containing the exposed plates or films is secured in place, the said invention in part comprising means to permit the developing fluid to be readily accessible to the side of the plate or film.

The invention further contemplates in such portable developing apparatus a developing compartment so constructed as to be not only light-proof once the adapter containing the exposed plates or films has been secured therein, but also to provide for the complete submergence of the plate or film in the developing solution by providing an overflow chamber into which the developing solution may readily flow when the adapter containing the plate or film is lowered into the developing compartment and which accommodates the excess of developing solution in an amount corresponding to the volume between

the safety slide and the plates or films in the adapter so that when the safety slides of the adapter are removed there will flow into the developing compartment sufficient liquid or solution to entirely cover the plates or films.

Heretofore in producing negatives or positives in plates or films it has been necessary to remove them from their adapters after exposure in a dark room, thereafter immersing them in trays or tanks containing the necessary solutions to carry on the process of developing. This method required unusual care and oftentimes long delay in producing the negatives and positives due to the lack of the necessary facilities of the dark room. On the other hand, by providing a portable, self-contained, daylight developing apparatus in accordance with the principles of my invention, the necessary tanks for carrying out the process of development may be readily carried to the place of exposure of the plates or films and the negatives or positives may thus be produced in a very short time and thereby definitely establish the results of the exposures.

This process of development may be found to be very useful in the production of quick results for newspaper work, when a saving of time is of the essence of importance; for the quick delivery of photographs from an airplane while in flight during times of peace as well as war times, or for the explorer or scientist who is far from his laboratory base and is desirous of obtaining positive results when engaged in photographing unusual objects wherein the necessity of learning the results of the exposure is of paramount importance.

Finally the invention is characterized by providing the comparatively simple and relatively inexpensive day light developing apparatus of a compact, portable form which may be used as a means for developing, fixing, washing and drying photographic plates or films without resorting to the dark room to the end that the operation may be performed in the field whenever it may be desirable or convenient to develop the same to prevent the deterioration or possible fading of the plates or films when, for example, a considerable

time would otherwise elapse between the exposure and the possibility of having access to a dark room for developing, and with this object in view the invention consists in the construction and combination of parts of which a preferred embodiment is shown in the accompanying drawing, in which:

Fig. 1 is a view in perspective showing generally the appearance of the developing apparatus;

Fig. 2 is a side elevation taken in section, illustrating the construction of the various compartments of the developing container;

Fig. 3 is a sectional view taken on the line 15 3—3 of Fig. 2;

Fig. 4 is an enlarged detail view of one corner of the container with the cover removed; and

Fig. 5 is an enlarged detail view of the 20 upper corner of the developing compartment illustrating the manner in which the light seal is effected.

Referring more particularly to the drawing wherein corresponding parts are designated by like numerals throughout the several views thereof, the apparatus in the preferred embodiment of my invention herein illustrated comprises generally a casing or container 10, which may be constructed of 25 wood or other suitable material that will hold the liquids necessary in the developing process. For convenience the casing is provided with an outer sheet metal covering indicated by numeral 11, a handle 12 having hooked 30 ends 13 extending through suitable reinforced openings 14 provided in the side walls of the container to permit the developing tank to be easily carried wherever desired. The inside of the casing 10 is formed with 35 a plurality of compartments, herein designated by numerals 15, 16, 17, 18 and 19 respectively, all being made of sheet metal suitably secured together as by soldering or the like, so that each compartment is made liquid- 40 proof. Each compartment may be constructed to accommodate plate or film holders of any particular size. In the present instance and for purposes of illustration, the various 45 compartments here shown being designed to accommodate a standard eight by ten plate holder.

Each compartment is provided with a separate cover, generally indicated by numeral 20, each cover being hinged to the casing 50 10 at one end, as shown by numerals 21, the other end of each cover being provided with a spring clip 22, each having an opening 23 provided therein, which are adapted to co-operate with pins 24 to maintain each cover 55 closed when the developing apparatus is not in use and thus prevent the solution contained in the various compartments from being spilled.

The compartment 15, heretofore mentioned, is so constructed as to form a develop- 60

ing chamber whereby the exposed plates or films may be rapidly developed as soon after exposed as it may be desired. This compartment is provided at its top with pairs of opposed plates of spring material, generally indicated by numeral 25 and at its bottom with pair of opposed plates of spring material generally indicated by numeral 26, which are soldered or brazed to the inside walls of the compartment and in spaced relation, as 70 indicated in Fig. 2. When the plate or film holder is positioned in the developing compartment, these plates serve the purpose of properly positioning the plate or film holder in the compartment and maintaining the 75 same spaced from the side walls of the developing compartment so that the developing solution may gain ready access to the surfaces of the plates or films in the holder. The spring retaining plates 25 and 26, heretofore mentioned, are of sufficient flexibility to permit manual insertion or removal of the plate or film holder during the developing process. Near its top end the developing compartment is provided with a longitudinally extending metallic strip 27 suitably secured to the side walls 28 of the developing compartment, as by soldering or the like. The opposite side wall 29 is formed with a socketed portion 30, within which is adapted 80 to be yieldably mounted a floating bar 31, a spring leaf 32 fastened to the rear wall 33 of the socketed portion 30, as by rivets 34, serving to urge the bar 31 outward and into 85 engagement with the film adapter. 90

The strip 27 and the floating bar 31 are both formed with opposed grooves 35 and 36 respectively, which extend lengthwise thereof, as shown by Fig. 3, and which are adapted to receive the tongues 37 and 38 forming a part 105 of the standard plate or film holder to provide a light-tight closure, which when the holder is in position in the developing compartment prevents light rays from striking 110 the sensitized surface of the photographic plate or film.

An overflow chamber 39, offset from the developing compartment as shown in Fig. 2 and having an elongated slotted opening 40 in direct communication with the compartment 15, accommodates the excess of developing solution in the developing compartment caused by the rise of the solution when the plate or film holder is lowered into the developing compartment. Openings 41 formed 115 in the side wall 42 of the overflow chamber, may also be provided to permit possible air trapped in the overflow chamber to readily escape.

By constructing a portable developing apparatus in the manner above described, the 120 possibility of the photographer carrying his own developing laboratory wherever desired is established. The method described above is found to be the most compact arrange- 125 130

- ment, being economical in construction and extremely light in weight. For example, an eight by ten standard plate holder is loaded with two sensitized photographic plates, two 5 exposures having been made. The holder containing the exposed plates is removed from the camera with the safety slides in place and thereafter immersed in the developing compartment of the developing apparatus, which same holds the developing solution. The dark or safety slides may then be removed and the process of development carried on for from two to eight minutes, the time depending on the type of developer used. 10 Before removing the holder containing the plates or films from the developing compartment, the safety slides are again inserted, the holder removed from the developing compartment and thereafter immersed in the quick-stop solution contained in compartment 16 and the safety slides again removed. After washing or rinsing from one-quarter to one minute the holder containing the plates or films is placed in the fixing solution in compartment 17 for from one and one-half 20 minutes to five minutes. The holder is then removed and immersed in the washing solution contained in compartment 18 for from one to five minutes, moving the holder containing the plates or films up and down rapidly in order to thoroughly wash the plates or films. 25

If it is desired to dry rapidly, the holder may next be immersed in the dryer solution contained in compartment 19 for from one-half to two minutes, after which it is exposed to the circulation of air. After the plates are thoroughly dried they may be removed from the holder, the entire process of developing 30 having been accomplished very rapidly in the field whenever desired and in the daylight.

While I have illustrated and described the preferred form of construction for carrying my invention into effect, it is to be understood that variations and modifications may be had without departing from the spirit of my invention. I therefore do not wish to be limited to the precise details of construction set forth, but desire to avail myself of such variations and modifications as may come within the scope of the appended claims.

Having thus described my invention, what I claim as new and desire to secure by Letters Patent is:

1. In a photographic film developing apparatus of the class described, a compartment for containing a fluid, a photographic film holder adapted to be received in said compartment whereby said fluid may chemically treat the sensitized portions of the film in said holder, and closure-forming means 45 in said compartment cooperating with said

film holder to form a light-tight joint therewith.

2. A photographic film developing apparatus having a compartment to receive a fluid, a film holder adapted to be received in said compartment whereby the film in said holder may be chemically treated, and closure-forming means including a yieldable member mounted in said compartment adjacent the upper end thereof cooperating with the exposed end of said film holder to form a light-tight closure therewith. 70

3. In a photographic film developing apparatus of the class described, a compartment for receiving a fluid, a photographic film holder adapted to be received in said compartment whereby said fluid may chemically treat the image-bearing portion of the film in said holder, a plurality of members mounted in said compartment and including a fixed member and a relatively movable spring actuated member, said members being spaced apart and so constructed and arranged that when said film holder is received in said compartment the sides of said film holder are engaged by said members to effect a light-tight joint between the holder and the sides of said compartment. 80

4. In a photographic film developing apparatus of the class described, a compartment for receiving a fluid, a photographic film holder adapted to be received in said compartment whereby said fluid may chemically treat the image-bearing portion of the film in said holder, oppositely disposed closure forming members mounted in said compartment, said members being spaced apart whereby when said film holder is received in said compartment the sides of said film holder are engaged by said members to effect a light-tight closure between the holder and the sides of said compartment, one of said members being movable relative to the other member and being yieldably mounted in said compartment. 90

5. In a photographic film developing apparatus of the class described, a compartment for receiving a fluid, a film holder adapted to be received in said compartment whereby the film in said holder may be chemically treated, closure forming members mounted in said compartment, one of said closure-forming members being movable relative to the other, said members being spaced apart and in opposed relation whereby when said film holder is received in said compartment the sides of said film holder are engaged by said members to effect a light-tight joint between the holder and sides of said compartment, and spring means cooperating with said relatively movable closure forming members to yieldingly urge said member and said film holder against the other closure-forming member to establish said light-tight joint. 100

6. A photographic film developing appa- 110

- ratus of the class described, comprising a compartment for receiving the fluid, a film holder adapted to be received in said compartment whereby the film in said holder
- 5 may be chemically treated, closure forming members mounted in said compartment, one of said members being movable relative to the other said members being spaced apart whereby when said holder is received in said
- 10 compartment the sides of said film holder are engaged by said members to effect a light-tight closure between the holder and the sides of said compartment, and an overflow chamber having an aperture in communication
- 15 with said compartment to permit the delivery and escape of fluid to and from said compartment whereby to maintain the level of fluid in said compartment above the edge of the film in said holder.
- 20 7. A photographic film developing apparatus of the class described, comprising a compartment for receiving a fluid, a film holder adapted to be received in said compartment, oppositely disposed closure forming members mounted in said compartment one of said closure-forming members being spring actuated and movable relative to the other member, said members being adapted to engage the sides of said film holder to
- 25 effect a light-tight closure therewith, and spacing members supported in the lower end of said compartment adapted for retaining said film holder spaced from the sides of said compartment so that the exposed portion of
- 30 the film will be freely presented to the chemical action of the fluid in said compartment.
- 35 8. A portable film developing apparatus for daylight photography, comprising a casing, a handle for said casing, a developing
- 40 compartment in said casing for receiving the fluid, a film holder adapted to be received in said compartment, oppositely disposed closure forming members mounted in said compartment one of said closure-forming members being spring actuated and being movably mounted relative to the other member and adapted to engage the sides of said holder to effect a light-tight closure therewith, a plurality of spring clips carried on the sides
- 45 of said compartment and cooperating with said film holder to retain the said film holder spaced relative to the sides of said compartment whereby the exposed portion of the film may be freely accessible to the chemical action of the fluid in said compartment, and an
- 50 overflow chamber having an aperture in communication with said developing compartment to permit the delivery and escape of fluid into and out of said developing compartment whereby to maintain the level of fluid in said developing compartment above the upper edge of the film in said holder.
- 55
- 60

In testimony whereof I affix my signature,
GEORGE A. MAGNUS.
